UNITED STATES PATENT OFFICE.

JOHN B. FREYSINGER, OF NEW BRITAIN, CONNECTICUT, ASSIGNOR TO NORTH & JUDD
MANUFACTURING COMPANY, OF NEW BRITAIN, CONNECTICUT.

BELT BUCKLE.

Application filed April 24, 1925. Serial No. 25,624.

This invention relates to belt buckles for personal wear and has special reference to the gripping jaw and the means for operating the same, the object being to provide a construction which will permit the jaw and the lever or handle to be rapidly and cheaply assembled and will effectually prevent separation after they are assembled. The invention is illustrated in the accompanying drawing and consists in certain novel features which will be particularly pointed out in the appended claims.

In the drawing:

Figure 1 is a rear elevation of a buckle showing one embodiment of the invention;

Figure 2 is a longitudinal section of the same;

Figure 3 is a detail section showing the jaw and the lever as they appear before being completely assembled;

Figure 4 is a detail perspective view of the jaw member;

Figure 5 is a view similar to Fig. 3 but showing a different embodiment of the invention;

Figure 6 is a section taken in a plane at a right angle to the plane of the section shown in Fig. 5;

Figure 7 is a detail perspective of the jaw shown in Figures 5 and 6.

The buckle body or face plate 1 is of the usual or any approved form provided on its side edges with belt-guiding and retaining flanges 2 constructed to receive the ends 35 of a pintle pin or pivot member 3, the ends of the pintle pin being upset against the outer sides of the flanges to secure the pin in place.

The gripping member or jaw includes 40 parallel transverse lips 4 and 5 connected by a bridge or head 6 and approximately equal in length to the distance between the flanges 2. The bridge 6 is integral with the lips and at the ends of the lip 4 are integral 45 ends walls 7 which, in the completed device, extend to the lip 5 and close the space between the ends of the latter and the lip 4, this construction facilitating production inasmuch as the entire jaw may be formed 50 from a single flat blank and easily bent into the required shape in a sheet-metal-stamping machine. Openings 8 are formed through the end walls 7 whereby the jaw may be hung upon the pintle 3, and in

the lip 4 are provided openings 9 to receive 55 the ends of the combined jaw-operating lever and belt retaining bail or loop 10, slots 11 being formed in the jaw across the corner defined by the head 6 and the lip 5 to effect engagement with the side members of 60 the bail, as shown. The closed end of the bail is wider than the open end thereof in order that it may be easily engaged by the attaching end of the belt and the sides of 65 the bail are offset laterally near their ends, as shown at 12, to extend between the slots 11 and the opening 9, the parts engaged in 70 the slots and the openings being in parallel planes, as shown in Figures 2 and 3; and the pintle extending through the space 70 bounded by the lip 4, the head and the offsets 12 and being eccentric to the gripper.

In practice, the bail or lever is engaged 75 through the slots 11 and in the openings 9 while the lip 5 is in slightly divergent relation to the lip 4 as shown in Figure 2, the bending of the lip being then completed so that it is brought into parallelism with the lip 4. The gripper is then positioned 80 between the flanges of the face plate or buckle body and the pintle 3 inserted through the openings provided therefor, the ends of the 85 pintle being upset against the flanges of the face plate as heretofore stated. The bail or lever cannot be withdrawn without, in effect, destroying the buckle, although the 90 openings 9 and the slots 11 are of such dimensions as to permit some play of the gripper so that it will accommodate itself to belts of different thicknesses.

In the form of the invention shown in 95 Figures 5, 6 and 7, the side members of the bail 13 are not laterally offset and the ends thereof are flattened, as at 14, to fit closely within the narrow slots or slits 15 formed in the head 16 and both lips 17 and 18 of the gripper, the pintle 19 being inserted through the ends of the gripper and the flanges of the face plate as usual and also passing 100 through openings provided therefor in the flattened ends of the bail.

It will be observed that in neither described form of the invention are the ends of the bail upset or riveted to the gripper, thus diminishing one item of expense in previously known devices, but in both forms the relation of the bail or lever to the pintle and the gripper is such that the bail can-

not be disengaged from the gripper and will operate efficiently to effect turning of the gripper to fasten or release a belt.

Having fully described my invention what 5 I claim as new and desire to secure by Letters-Patent, is:—

1. In a belt buckle, the combination of a face plate, a pintle mounted at the rear of the face plate, a gripper mounted for 10 rocking movement upon the pintle and having lips, a head connecting the rear edges of the lips, and end walls between the corresponding ends of the lips and through which the pintle passes, there being openings through the lips, and a lever bail having its ends fitted through the openings in the lips and free therein and held by the pintle against withdrawal.
2. In a belt buckle, the combination of a 20 face plate, a stationary pintle mounted at the rear of the face plate, a gripper mounted eccentrically on the pintle and consisting of lips, a head connecting the lips and end walls closing the spaces between corresponding ends of the lips, there being openings in one lip and in the junction of the other lip and the head, and the pintle extending through the end walls, and a lever having one end fitted loosely in the open-

ings in the lips and held in the gripper by 30 the pintle.

3. In a belt buckle, the combination of a face plate, a pintle mounted at the rear of the face plate, a gripper consisting of lips and a head connecting the rear edges 35 of the lips mounted on the pintle for rocking movement and having openings in its lips and a lever bail having its ends engaged in openings in the lips of the gripper and offset within the gripper to pass 40 around the pintle and be held in the gripper.

4. In a belt buckle, the combination of a face plate, a pintle mounted at the rear of the face plate, a gripper mounted for rocking movement on the pintle and consisting of parallel lips and a head connecting the rear edges of the lips, there being 45 openings through one of the lips and slots in the head at the other lip, the pintle being located nearer the lip having the openings therethrough, and a lever bail having its ends engaged through the slots and the openings and offset within the gripper to pass between the pintle and one lip.

In testimony whereof, I have signed this 55 specification.

JOHN B. FREYSINGER.
